UNITED STATES PATENT OFFICE.

WILLIAM S. HADAWAY, JR., OF NEW YORK, N. Y.

REGULATOR FOR ELECTRIC FLUID-HEATERS.

1,080,214.

Specification of Letters Patent.

Patented Dec. 2, 1913.

Application filed September 5, 1911. Serial No. 647,698.

To all whom it may concern:

Be it known that I, WILLIAM S. HADAWAY, Jr., a citizen of the United States, residing at New York, in the county of New York and State of New York, have invented new and useful Improvements in Regulators for Electric Fluid-Heaters, of which the following is a full, clear, concise, and exact description, reference being had to the accompanying drawing, forming a part of this specification.

My invention relates to regulators for electric fluid heaters.

It more especially relates to electric fluid heaters of the type wherein the fluid is in circuit and is heated by the passage of current through the same.

My invention has among its objects to provide an improved regulator for electric fluid heaters by the use of which said fluid heaters may be adapted to heat fluids of widely different resistances to widely different temperatures.

A further object of my invention is to provide an improved regulator for electric fluid heaters wherein the amount of fluid in circuit may be readily varied as desired by adjusting the heater with respect to its source of fluid supply or vice versa.

30 A further object of my invention is to provide a simple, inexpensive and rugged regulator which may be constructed and installed with small expense and which is adapted to provide a large range of regulation.

35 Other objects and advantages of my improved construction will hereinafter appear.

In the views of these drawings I have illustrated two forms which my invention may assume in practice. My invention is 40 not, however, limited to these forms chosen for purposes of illustration, but may assume other forms.

In the views of these drawings:—Figure 1 shows a partial sectional view of one form 45 of heater equipped with my improved regulating means. Fig. 2 shows a modified form of regulating means for the heater. Fig. 3 shows a detail of construction.

In the construction shown in these drawings I have for purposes of illustration

shown an electric water heater of the carbon electrode type wherein the fluid is in circuit and a plurality of carbon electrodes 1 are immersed in a fluid containing casing 2 provided with a suitable outlet 3 and a suitable 55 inlet 4. The inlet 4 is connected to a source of fluid supply such as a tank 5 by means of a flexible tubing 6. The amount of fluid in the tank 5 is regulated by a float 7 controlling an inlet valve 8. In order to counter-balance the heater a weight 9 is provided suspended from a suitable rope or cable 10 over one or more pulleys 11.

In my improved construction I have taken advantage of the fact that when two receptacles containing a liquid are connected the level of the liquid will tend to become the same in both, and have so arranged the heater that it is movable with respect to the source of fluid supply, a flexible connection 65 being provided between the same which serves to connect the bodies of water in the two receptacles. When the heater is moved upward the water within the same will not reach any higher level than that of the water 70 within the tank and consequently a greater amount of electrode surface within the heater will be exposed as the liquid recedes. Thus the amount of liquid in circuit will be varied and as the resistance will be decreased, this resistance may be adjusted to any satisfactory amount by simply moving the heater vertically with respect to the tank. By the provision of the counterweight 8 the 75 heater will be held in any position to which it is moved, although other means for holding the heater may be provided. By the provision of the flexible tubing connecting the heater and the tank, it is obvious that the liquid may flow from the tank to the heater 80 or vice versa when either of these members are in any desired position. It is of course also obvious that instead of the heater being moved the source of liquid supply may be adjusted relatively to the heater to vary the 85 water level in the heater.

In Fig. 2 I have illustrated a modified form of the construction shown in Fig. 1. In this construction the electric heater, the source of fluid supply and the connection 90

between the same may be the same as those illustrated and described in connection with Fig. 1. However, in this instance instead of the counterweight I have illustrated a 5 threaded shaft 12 arranged to be rotated by a suitable hand wheel 13. One end of the threaded shaft 12 may be suitably fixed to the heater casing 2 and may be supported and guided in any suitable guiding member 10 or bracket 14 which in turn may be supported on any suitable wall or bracket. When the handle 13 is rotated it is desirable to have some means to prevent the rotation of the casing 2 and in order to prevent 15 this rotation I have provided a projection or tooth 15 which is carried upon the inner periphery of the guiding member 14 and which engages with a longitudinally extending groove 16 in the threaded shaft 12. By the provision of this improved means of adjusting the heater, an operator may by simply turning the hand wheel readily adjust the heater to any desired level to adapt the same to heat any desired 20 liquid to any desired temperature.

By my improved construction I have provided a simple regulator which may be readily adapted to heaters of many different types and one which does not require fitting 25 within the casing of the heater but may be attached to the same without any change in the construction of the heater. Further, my improved regulator is adapted to use in large installations wherein large batteries 30 of electric heaters are employed and it is desired to vary the temperature of the liquid heated by the same. By the use of my improved construction a rugged regulator is provided which may be operated with ease 35 by an unskilled operator and which will provide a large range of regulation. Further, the parts of the same are so exceedingly simple that there is little or no danger of the regulator becoming out of order. Further 40 by my improved construction the water level within the heater may also be readily varied by varying the adjustment of the float within the tank so that the liquid level in the tank may be adjusted. By the provision 45 of either the counterbalance or the threaded shaft, the heater may be held in any position to which it is moved. This range of movement may be exceedingly large as the tubing connecting the heater and the source 50 of fluid supply may be of any desired length. Further by my improved construction the regulating apparatus is so arranged that it does not interfere with the parts of the heater.

55 While I have in this application described two specific forms which my invention may assume in practice, I do not wish to be limited to these forms chosen for purposes of illustration but wish rather to include in the

scope of this application all those forms of my invention falling within its spirit.

What I claim as new and desire to secure by Letters Patent is as follows:—

1. The combination with a fluid heating device, of a fluid containing device for supplying fluid to said heating device, one of said devices being adjustable with respect to the other to vary the height of the fluid in said heating device.

2. In combination, a fluid heating device, a fluid containing device for supplying fluid to said heating device, means for maintaining a substantially constant fluid level in said second device, and means for adjusting one of said devices with respect to the other to vary the volume of fluid in said heating device.

3. In combination, a fluid heating device, means for supplying fluid thereto and maintaining a substantially constant level of the fluid therein in a fixed position thereof, and means for adjusting said heater to vary the volume of fluid therein.

4. In combination, a fluid heater, means for supplying fluid thereto and maintaining a substantially constant level of the fluid in said heater, and means enabling relative adjustment of said heater and said fluid supplying means to vary the volume of fluid in said heater.

5. In combination, a fluid heater, a fluid supplying reservoir therefor connected to a source of fluid supply and means for maintaining a substantially constant level of the fluid in said reservoir, said heater being adjustable relative to said reservoir to vary the volume of fluid in said heater.

6. In combination, a fluid reservoir connected to a source of fluid supply, a float actuated device for controlling the supply of fluid to said reservoir to maintain a substantially constant level of the fluid therein, a fluid heating device supplied with fluid from said reservoir, and means for varying the vertical position of said heater to vary the volume of fluid therein.

7. In combination, a fluid reservoir connected to a source of fluid supply, a float actuated device for automatically controlling the supply of fluid to said reservoir to maintain the fluid level of said reservoir substantially constant, a fluid heater, a flexible fluid supply connection between said reservoir and said heater, and means for varying the vertical position of said heater to vary the normal level of the fluid therein.

8. In combination, a fluid heater and means for supplying fluid thereto including an automatic device external to said heater but responsive to variations in the level of the fluid therein to maintain the level of the fluid in said heater substantially constant.

9. In combination, a fluid heater, means

for supplying fluid thereto including an automatic device external to said heater but responsive to variations in the level of the fluid therein to maintain said level and 5 means for adjusting said heater vertically to vary the volume of fluid therein.

In witness whereof, I have hereunto sub-

scribed my name in the presence of two witnesses.

WILLIAM S. HADAWAY, Jr.
